R. H. INVENTOR,
Ingersoll
BY L. A. Hill & Co
ATTORNEYS,

UNITED STATES PATENT OFFICE.

ROBERT H. INGERSOLL, OF NEW YORK, N. Y.

KEY-RING.

SPECIFICATION forming part of Letters Patent No. 398,835, dated March 5, 1889.

Application filed June 13, 1888. Serial No. 277,022. (No model.)

To all whom it may concern:

Be it known that I, ROBERT H. INGERSOLL, a citizen of the United States, and a resident of New York, in the county and State of New York, have invented certain new and useful Improvements in Key-Rings, of which the following is a specification.

My invention relates especially to devices employed in supporting and holding securely together keys and like articles, and has for its object the provision of a device simple in construction, cheap in manufacture, and efficient in practical use.

To attain the desired end my invention consists in the construction and arrangement of parts hereinafter fully set forth.

In the drawings which form a part of this specification, Figure 1 represents a view of my ring. Fig. 2 is a side and Fig. 3 an edge view of my clasp. Fig. 4 is a side and Fig. 5 is an edge view of my combined ring and clasp, and Fig. 6 is a view of a modification of my invention.

Like letters of reference wherever they occur indicate corresponding parts in all the figures.

Referring again to the drawings, A represents my key-ring, which is provided with notches *a* in the upper edges of both ends. The clasp B is constructed so as to fit over and entirely cover the notches and ends of the ring, and is provided with cross-bars *b*, adapted to engage in the notches *a*. The ring A is constructed out of spring metal, and, on account of the resiliency of the same, whenever the clasp B is secured to or sprung on the ring A, as represented in Fig. 4, it becomes locked upon the same, and it thereupon cannot be detached until the two ends of the ring A are pressed together, thus allowing the cross-bars

b to pass through and become disengaged from the outwardly-turned notches *a*.

The notches *a* may be curved so as to turn outwardly, as in Fig. 1, or inwardly, as represented in Fig. 6, the relative action of the 45 clasp B and ring A being similar in both cases, the key-ring A, however, whenever it is desired to attach or release the clasp B, being compressed in the one instance and the ends of the same being pulled apart in the 50 other.

By the use of my device the keys or other articles will be securely held on the ring, as the clasp is normally locked thereon, and as it is impossible to detach the same by pulling or 55 pushing the same until the ring is properly manipulated by having the ends thereof pressed together or pulled apart, as the case may be.

What I claim as new, and desire to secure 60 by Letters Patent, is—

The combination, with a key-ring constructed of spring metal and provided with inclined notches *a*, placed in the upper edges of both ends, of a detachable clasp, B, constructed so as to fit over and cover the notches and ends of the ring and provided with cross-bars *b*, adapted to engage with the notches *a* and to be securely locked therein by the resiliency of the ring, substantially as 65 70 described.

In testimony of the foregoing specification I do hereby sign the same in the city of New York, county and State of New York, this 14th day of April, A. D. 1888.

ROBERT H. INGERSOLL.
